UNITED STATES PATENT OFFICE.

WILLIAM D. BRADFORD, OF SEWICKLEY, PENNSYLVANIA.

BOX FOR POURING STEEL INGOTS.

1,398,584.

Specification of Letters Patent. Patented Nov. 29, 1921.

Application filed December 13, 1920. Serial No. 430,360.

To all whom it may concern:

Be it known that I, WILLIAM D. BRADFORD, a citizen of the United States, residing at Sewickley, in the county of Allegheny and State of Pennsylvania, have invented a new and useful Box for Pouring Steel Ingots, of which the following is a specification.

This invention relates to boxes for pouring steel into molds, one of its objects being to provide a structure of this character whereby two molds can be filled at one operation, the flow of steel to the molds being controllable at all times so that more or less of the molten steel can be directed to either of the molds.

A further object is to provide a pouring box whereby the ingots will be poured slowly thus doing away with the cracking resulting from rapid pouring of the steel. It is well known to those skilled in the art that unless the ingots are poured slowly the cracks will be produced and this has resulted in the use to a large extent of a plate known as a bottom cast. Bottom cast ingots are much more expensive than top cast ingots but nevertheless the top cast ingots usually have a great number of surface cracks which open up when the ingot is rolled.

It is an object of the present invention to provide a pouring box whereby by reducing the flow of steel the formation of cracks is practically eliminated, the pressure of the stream as it comes from the ladle being taken up by the pouring box and said stream being split so that a portion will go to one mold and the balance to another mold, the flow being much slower than should the steel be poured directly from the ladle into the mold.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a plan view of a carriage having the pouring box mounted thereon.

Fig. 2 is a front elevation of the carriage and pouring box, said box being located above two ingot molds.

Fig. 3 is an enlarged plan view of the pouring box.

Fig. 4 is a view partly in elevation and partly in section of the pouring box.

Fig. 5 is a central vertical transverse section through the pouring box.

Referring to the figures by characters of reference 1 designates a suitably constructed carriage adapted to travel along a supporting track indicated at 2. This carriage has 70 spaced arms 3 extending laterally therefrom and tiltably mounted between the arms is a pouring box such as has been illustrated in detail in Figs. 3, 4 and 5. This box includes a top plate 4 having lifting lugs 5 at the ends thereof and upstanding from the center of this plate is a split tapered sleeve 6 in which is seated a conical funnel or fountain 7 of suitable refractory material. Secured to the top plate 4 is an elongated housing 8 having 75 depending end portions 9 and a recessed central portion 10. In this central portion is secured a lining of firebrick or the like indicated at 11 while within the depending portions 9 are arranged nozzles 12 of refractory material. Hollow refractory blocks 13 are seated within the housing 8 and constitute linings therefor whereby the molten steel is conducted from the central funnel or fountain 7 to the nozzles 12. The cement used for fastening the blocks within the housing 8 and to the plate 4 and sleeve 6 has been indicated at 14.

Extending from the sides of the housing 8 at the center thereof are trunnions 15 overhung by guard plates 16 and these trunnions are supported within the sides of the arms 3 as shown particularly in Fig. 2.

When it is desired to use the device herein described the ingot molds, indicated at A in 100 Fig. 2 are placed in position and the pouring box is then brought into place above the molds by moving the carriage 1 along the track 2. A bar, shown at 17, can be inserted into one of the lugs 5. The ladle is then 105 filled with molten steel and brought to position above the pouring box so that the stream of molten steel will pass from the ladle into

the funnel or fountain 7. This pouring box will thus receive the force of the pouring steel which steel will be divided into two streams, passing to the respective nozzles 12 5 as will be obvious. Small jets of molten steel will thus issue from the nozzles and flow into the respective ingot molds. Should the steel flow too rapidly from one of the nozzles the box can be tilted by means of the 10 bar 17 so as to direct more of the steel to the other nozzle.

What is claimed is:

1. A closed box for pouring steel into ingot molds having spaced nozzles, an intermediate steel receiving fountain carried by and 15 opening into the box, and covered means within the box for conducting molten steel

from the fountain and within the box to the respective nozzles.

2. A box for pouring steel into ingot 20 molds including a tiltably supported covered housing, nozzles extending downwardly within the end portions of the housing, an intermediate steel receiving fountain, and means for conducting streams of molten 25 steel from the fountain to the respective nozzles.

In testimony that I claim the foregoing as my own, I have hereto affixed my signature in the presence of two witnesses.

WILLIAM D. BRADFORD.

Witnesses:

JAMES EDWARD CULLETON, Jr.,

WILLIAM DICKINSON SHIELDS.
